UNITED STATES PATENT OFFICE.

WILLIAM D. CARTER, OF SAN JOSE, CALIFORNIA.

HYDRAULIC BALANCE FOR CENTRIFUGAL PUMPS.

1,267,512.

Specification of Letters Patent. Patented May 28, 1918.

Application filed December 12, 1916. Serial No. 136,464.

To all whom it may concern:

Be it known that I, WILLIAM D. CARTER, a citizen of the United States, residing at San Jose, in the county of Santa Clara and 5 State of California, have invented new and useful Improvements in Hydraulic Balances for Centrifugal Pumps, of which the following is a specification.

This invention relates to a hydraulic balance for centrifugal pumps, and pertains 10 particularly to improvements in pumps of the type illustrated in my co-pending application filed on or about May 29th, 1916, Ser. No. 100,712.

One of the objects of the present invention 15 is to provide a simple, substantial, cheaply manufactured multi-impeller pump, and particularly a hydraulic balancing device which will relieve the impeller from what is commonly called "end thrust", said 20 hydraulic balancing device being so constructed and arranged that it will be equally efficient whether the impellers are operating in series or in parallel, or in multiple series, 25 or as a double-suction, impeller, single-stage pump or as a multi-stage pump. Another object of the invention is to provide an automatic, hydraulic balancing device which is particularly applicable where a double impeller is used and which acts with comparatively equal efficiency whether an odd or even number of double impellers is employed. Further objects will hereinafter appear.

The invention consists of the parts and 30 the construction and combination of parts as hereinafter more fully described and claimed, having reference to the accompanying drawings, in which—

Figure 1 is a vertical cross section of a 40 double service centrifugal pump, taken on line 1—1 of Fig. 2, showing the cylindrical casing in position for combining the volumes received from the two sides of the 45 double impeller, with the result commonly obtained with the ordinary type of double-suction impeller pump; this view also giving the location of the hydraulic balancing ports.

Fig. 2 is a plan view, in section, taken on

line 2—2 of Fig. 1, said view being partly broken away to show the ports in the main base casing.

Fig. 3 is a cross section on line 3—3 of Fig. 4; the cylindrical casing being shown 55 revolved on its seat in the main base casing to a position required for combining the independent discharges of the two sides of the double impeller in series, thus obtaining the result commonly secured with an ordinary type of two-stage pump.

Fig. 4 is a plan view, in section, taken on line 4—4 of Fig. 3, with part of the cylinder casing broken away to expose ports in the main base casing through which water 60 passes when the two sides of the impeller are connected in series.

Fig. 5 is a plan view, in section, of the base casing, taken on line 4—4 of Fig. 3.

Fig. 6 is an enlarged cross section of the 70 double impeller.

Fig. 7 is a side elevation of same.

Fig. 8 is a side elevation of the cylinder casing, showing the position of the several intake and discharging ports.

Referring to the drawings in detail, A indicates a base casing in which are formed two main passages, such as indicated at 2 and 3. The passage 2 connects, at one end, with a main suction elbow 4, and at the opposite end with a port 5. The passage 3 connects at one end with a port 6 and at the opposite end with a port 7.

Formed at one side of the base casing is a main discharge port 8, and forming an impression in the interior of the casing is a passage 9, the purpose of which will herein-after be described. Turnably mounted and supported in the base casing is a cylindrical casing B which may herein-after be termed the "volute." Formed in said casing are two volute passages 10 and 11 which are arranged side by side. These volute passages are symmetrically disposed with respect to a plane half-way between them and are, furthermore, perpendicular to a main driving shaft 12 which extends through the base casing and the volute. Suitably secured upon the shaft interiorly of the volute casing is a double impeller, such as indicated at 13. 100

This impeller is provided with two aligned suction openings 14 and 15 and two separate annular discharging passages 17 and 18 in which are formed impeller blades 19.

- 5 Formed in the volute casing and communicating with the volute passages 10 and 11 are a pair of ports 20 and 21, and formed in alignment with said ports is a third port 22 which communicates through a passage 10 23 with the suction side of the discharge passage 18 formed in the impeller. Formed in the opposite end of the base casing is a central opening which communicates with the suction side of the discharge passage 17.
- 15 On each side of the impeller are formed concentric inner and outer annular flanges 14^a—14^b, to coöperate with corresponding cylindrical surfaces 14^c—14^d, inner flange 14^a surrounding the intake port 14 or 15, 20 and forming a running joint with the annular flange 14^c in the main casing, the outer flanges 14^b forming running joints with corresponding cylindrical surfaces 14^d on the volute casing; flanges 14^a—14^b on one side 25 of the impeller form with the adjacent side of the volute casing a counter-balancing chamber 27 while the other part of flanges 14^a—14^b on the opposite side of the impeller form a counter-balancing chamber 25 30 with the adjacent side of the base casing; all as will be later described.

The pump constructed as here shown and provided with a double impeller may either operate in parallel as a double-suction, single-stage pump, or in series as a two or multi-stage pump. This is accomplished by turning the volute casing B within the base casing to bring the ports 20, 21 and 22 into register or out of register with certain ports, 40 hereinafter to be described, which are formed in the base casing.

If it is desired to operate the pump as a double-suction, single-stage unit, it is accomplished by turning the volute casing until 45 the ports 20 and 21 register with the main discharge port 8, as shown in Figs. 1 and 2. The port 22 will then be in register with the passage 2 and it will, therefore, be possible for the water entering the suction elbow 4 to 50 take the following path: Part of the water will enter the intake 14 and discharge through the annular discharge of the impeller 17 into the volute passage 10 and from said passage through port 20 into the discharge port 8. Similarly, it is possible for water to pass from the suction elbow, 55 through the passage 2, to the opposite side of the impeller, where it enters through the intake 15 and passes out through the annular discharge passage 18 in the volute 11, from where it discharges through port 21 into the discharge port 8. Two separate volumes having the same pressure are in

this manner combined and discharged through the passage 8 and the action of the 65 pump becomes similar to a double-suction, impeller single-stage pump.

The foregoing construction corresponds closely to that described in my aforesaid co-pending case embodying essentially a pump 70 casing having a double impeller with two completely independent stream passages separated by a transverse partition, manifold passages having ports arranged so that by rotating the casing to selected positions 75 the impeller passages are connected in series, in parallel or multiple series.

The hydraulic balancing of the impeller, when so operated, will be as follows: Formed in the volute casing, exteriorly of the volute 80 passages 10 and 11, is a passage 24. One end of this passage communicates with the volute passage 11, while the opposite end communicates with the chamber 25 formed on one side of the impeller. Formed in the 85 volute casing, on the side opposite to the chamber 25, is a port 26, one end of which communicates with passage 23, while the opposite end communicates with the chamber 27, similar to chamber 25. 90

The balancing action of the passage 24 and the port 26 will be as follows: With water entering the suction elbow 4 it may be assumed that the pressure in the intake openings 14 and 15 of the impeller will be zero 95 and that the pressure in the volute passages 10 and 11 will be forty pounds. This pressure will, therefore, be established in chamber 25 as water is permitted to enter said chamber through the passage 24 from the 100 volute 11. This pressure will tend to force the impeller in the direction of arrow *a*, but the movement of the impeller is resisted as chamber 27 will gradually build up a pressure equal to that contained in chamber 25, 105 by pressure admitted from the volute 11 by leakage around the exterior outer flange 14^b. This pressure would be maintained in chamber 27 so long as the side of the impeller runs in close proximity to the outer flat edge 110 or face of the inner flange 14^c and closes port 26, thereby shutting off leakage into passage 23; while pressure in chamber 25 would be diminished by the full effect of unrestricted leakage around the inner flange 115 14^a to the suction elbow 4. Should this pressure become greater than the pressure in chamber 25, it can readily be seen that the impeller will move in a direction opposite to arrow *a*. Port 23 will, therefore, become 120 uncovered and the water contained under greater pressure in chamber 27 would discharge into the passage 23 which contains zero pressure. A perfect balance is in this manner obtained without resorting to any 125 complicated mechanism or any thrust bear-

ings or mechanism which would require care and attention.

If the pump is to be operated in series as a two-stage pump, it is accomplished by 5 turning the volute casing until it assumes the position shown in Figs. 3 and 4. Port 20 will here register with the port 6, port 21 with the depression 9, and port 22 with port 7. The water entering the suction elbow 4 10 would, therefore, take the following series circuit: It would first enter the intake 14 and the volute 10 from where it would discharge through ports 20 and 6 into the passage 3, which, as before described, communi- 15 cates with port 7. It will then pass through port 7 and port 22 into the passage 23, which connects with the intake side 15 of the impeller. The water will then pass through the annular discharge 18 of the impeller and 20 enter the volute passage 11 and would finally discharge through port 21 into the depression 9 which communicates with the dis- charge port 8.

The operation of the hydraulic balance 25 will in this instance be as follows: Assuming the pressure in the suction elbow to be zero, and the pressure in the volute 10 to be forty pounds, the pressure at the intake side 15 of the impeller would also be forty pounds 30 as the water is here received from the volute 10. The water, after its passage through this side of the impeller, will discharge into the volute 11 and will here have an additional pressure which, according to theory, 35 should be approximately eighty pounds. The port 26 and the passage 24 are, however, so arranged that they may operate whether the pressure in the several passages is equal or otherwise.

40 This will be more readily understood from the following: If the pressure on the intake side 14 of the impeller is zero and the pressure in the volute 10 is forty pounds, then the pressure in the intake side 15 of the impeller will be forty pounds and the pressure 45 in the volute 11 will be eighty pounds. The pressure in chamber 25 also will be eighty pounds as it is supplied with water through the passage 24 from the volute 11 and the 50 pressure in chamber 27 will also be eighty pounds as it is supplied with water by leak- age from the volute 11 around the annular running flange 14^b. The pressure at each 55 end of the runner is, therefore, practically speaking, equal, and in building up, the pres- sure will cause the impeller to move to or away from the port 26, in this manner re- lieving or building up pressure as conditions require. The hydraulic balancing arrange- 60 ment employed is equally efficient whether the pump is operated in series or in parallel or in multiple series.

There is nothing complicated about this

pump. It has one double impeller, each side of which discharges into the base through a 65 separate volute passage in the volute casing.

The base casing contains two sets of water 70 passages, only one of which is in use at a time. They are of large cross-sectional area and serve to connect the independent streams 75 from the two sides of the impeller either in series or parallel, according to the angular position of the volute in the base casing. That is, one position of the volute casing will throw the combined volume of both sides of 80 the impeller against a single pressure, while another position will discharge the single volume of one side of the impeller through the other side, thereby giving twice the pres- 85 sure. The construction is such that the 90 volute cannot rust tightly in the base casing.

For variable service each half of the im- 85 peller is designed to give as wide a range of variation in head as is possible with a well- 90 designed single impeller pump, and it is evi- dient that the combination of the two sides will give a continuous, uniform range of effi- 95 cient service approximately twice that of any other single impeller pump now on the market.

It is not necessary to disturb either the 95 suction or discharge connection in order to inspect the interior of this pump. Both sides of the impeller can be reached without removing it from the pump body, or, if de- 100 sired, the runner and shaft may be removed entirely by loosening the set-screw in the shaft coupling, not here shown.

Having thus described my invention, what 100 I claim and desire to secure by Letters Pat- ent is—

1. In a centrifugal or similar pump hav- 105 ing two or more double service impellers each capable of series or parallel operation, a pair of suction passages and a discharge passage connected with each impeller, means for changing the connection of said pas- sages so that said impellers may be operated in series, in parallel or in multiple series, and 110 a hydraulic end-thrust balancing means for automatically balancing the impellers whether the device is operated in series, in parallel or in multiple series.

2. In a centrifugal pump, the combination 115 of a casing and a double impeller therein having two independent stream passages sep- arated by a transverse partition, means by which said passages operate in series, or in parallel, counter-balancing means for the impeller whereby the impeller is automatic- 120 ally counter-balanced irrespective of whether the pump operates in series or parallel.

3. In a centrifugal pump, the combina- 125 tion of a casing, an impeller therein having two independent stream passages separated

- by a transverse partition, a pair of concentric flanges on each side of the impeller, corresponding flanges on the casing coöperating with the flanges on the impeller to form 5 a hydraulic counter-balancing chamber on each side of the impeller, each of said counter-balancing chambers being in leakage connection with the intake, and also in leakage connection with a respective discharge 10 column of said stream passages, and connections between the chamber of lower pressure with the discharge column of higher pressure when the pump is operating in series.
4. The combination in a centrifugal pump 15 of impellers operating in series, a counter-balancing chamber at each end of the series, each counter-balancing chamber being in leakage connection with the discharge to which said chamber is immediately adjacent, 20 and means by which the discharge at highest pressure is connected with the counter-balancing chamber of lowest pressure.
5. The combination in a centrifugal pump having a double flow impeller operating in 25 series, of means for hydraulically balancing the two sides thereof.
6. The combination in a centrifugal pump 30 having a double impeller operating in series, and automatic hydraulic counter-balancing chambers on the two sides of said impeller with means for connecting the side of high pressure of the pump with the counter-balancing chamber on the low pressure side of the pump.
- 35 7. In a centrifugal pump, a double flow impeller, a casing inclosing said impeller, and a hydraulic balancing chamber formed in the casing at each end of the impeller.
8. In a centrifugal pump, a double flow 40 impeller, a casing inclosing said impeller, a hydraulic balancing chamber formed in the casing at each end of the impeller, means for admitting water under pressure to said chambers, and means for automatically maintaining a balancing pressure in said 45 chambers.
9. In a centrifugal pump, an impeller 50 having a pair of opposed intake openings and a pair of spaced independent annular discharge passages, a casing inclosing the impeller, said casing having a pair of passages formed therein into which the impeller discharges, a balancing chamber formed in the casing at each end of the impeller, means for admitting water under pressure from one volute passage to one 55 balancing chamber, and a connection formed between the opposite balancing chamber and one of the intake passages of the impeller.
- 60 10. In a centrifugal pump, an impeller having a pair of opposed intake openings and a pair of spaced independent annular discharge passages, a casing inclosing the

impeller, said casing having a pair of passages formed therein into which the impeller 65 discharges, a balancing chamber formed in the casing at each end of the impeller, means for admitting water under pressure from one volute passage to one balancing chamber, a connection formed between the opposite balancing chamber and one of the intake passages of the impeller, and means for automatically cutting off said connection.

11. In a centrifugal pump, an impeller 75 having a pair of opposed intake openings and a pair of spaced independent annular discharge passages, a casing inclosing the impeller, said casing having a pair of volute 80 passages formed therein into which the impeller discharges, a balancing chamber formed in the casing at each end of the impeller, means for admitting water under pressure from one volute passage to one balancing chamber, and a connection formed 85 between the opposite balancing chamber and one of the intake passages of the impeller, said connection being adapted to be opened and closed by endwise movement of the impeller.

90 12. In a centrifugal pump, the combination of a casing and a double impeller therein having two independent stream passages separated by a transverse partition, means by which said passages operate in series, and counterbalancing means for automatically balancing said impeller against end-thrust.

13. In a centrifugal pump, the combination of a casing, an odd number of double impellers therein assembled upon one driving shaft, each of said impellers having two independent stream passages separated by a transverse partition, means by which said passages operate in series, and hydraulic counterbalancing means for automatically balancing said impellers against end-thrust.

14. In a centrifugal pump, the combination of a casing, an impeller therein having two independent stream passages separated by a transverse partition, a pair of concentric flanges on the low pressure side of said impeller, and a large flange on the high pressure side of said impeller, corresponding flanges on the casing coöperating with the flanges on the impeller to form a hydraulic 110 counterbalancing chamber on each side of the impeller, each of said counterbalancing chambers being in leakage connection with the intake, and also in leakage connection with a respective discharge column of said 115 stream passages, and connections between the chamber of lower pressure with the discharge column of higher pressure when the pump is operating in series.

15. The combination in a centrifugal 120 pump, of double impellers operating in

series, a counterbalancing chamber at each side of each impeller, each counterbalancing chamber being in leakage connection with the discharge to which said chamber is immediately adjacent, an exhaust passage leading from one or more of said chambers to a passage of lower pressure, and means for automatically opening and closing said exhaust passage by endwise movement of said impellers.

16. The combination in a centrifugal

pump having an odd number of double impellers operating in series, and means for hydraulically balancing the end-thrust of said impellers.

In testimony whereof I have hereunto set my hand in the presence of two subscribing witnesses.
